UNITED STATES PATENT OFFICE.

LOUIS GATHMANN, OF CHICAGO, ILLINOIS.

METHOD OF REDUCING LOBATED GRAIN.

SPECIFICATION forming part of Letters Patent No. 299,375, dated May 27, 1884.

Application filed October 11, 1883. (No specimens.)

To all whom it may concern:

Be it known that I, LOUIS GATHMANN, of Chicago, in the county of Cook and State of Illinois, have invented certain new and useful 5 Improvements in Methods of Reducing Lobated Grain in the Production of Coarse Middlings or Farina and Flour; and I do hereby declare that the following is a full, clear, and exact description thereof.

10 This invention relates to a novel process or method in the manufacture of flour, farina, coarse middlings, or flour from wheat or other lobated grain; and it consists, essentially, in the operations hereinafter described and claimed.

15

I first describe the method in the order of the steps and with reference to the particular operations which I prefer to adopt in this invention, and will subsequently point out certain modifications which I intend shall be embraced in my appended claim.

The first operation is decortication of the grain by any suitable or well-known means for the purpose, either chemical or mechanical, it 25 being understood that in this operation of decortication a surrounding integument is left about the starchy body after the operation of decortication, as practiced by known means, has been completed. Next the grain is split 30 through the crease, also by any well-known devices for the purpose. After the splitting has been performed and the kernels divided into parts or halves, the germ and crease impurities are of course exposed. In this condition the grain is subjected to another operation of decortication by any one of the means well known for the purpose that it will be thought best to employ. In this operation I have found that the thin film or layer which 35 incloses the starchy body will not be removed, but that the outer bran substance, which in the previous operation of decortication was concealed and protected within the crease, will be removed, leaving the thin layer or inner portion of the original integument now embracing all parts of the half-kernels that were previously covered by the bran. Next the half-kernels are separated from the bran substance removed by the operations of de- 45 cortication and from the germ and crease impurities and the minor fragments which have been detached in said operations of de-

cortication, leaving clean large fragments or half-kernels inclosed, principally, by the thin interior layer or filament of the original integument. These fragments are in this condition subjected to a grinding operation by any suitable means known in the art, but preferably by millstones. The product will be composed of two parts, one comprising about nine-tenths 55 of the entire decorticated grain substance, forming an exceptionally-pure flour and middlings, varying in relative proportions according as the stones are set to grind high or low with reference to the particular character of 60 the product in this respect desired. The remaining portion of the product will consist of the bran filament referred to, together with parts of the starchy substance adhering thereto, and this second part is subjected to purification by the ordinary purifying devices employed in mills for this purpose. The first portion of the product above mentioned, comprising nine-tenths of the entire food substance of the berry, will usually be of such purity as 65 to require no purification whatever, but may be reduced to any desired extent, or separated 70 into coarse and fine products—as farina and flour—for any further separate treatment or use desired.

As a modification, I would state that the grain may be split before any decorticating operation is performed thereon, and in this case the decortication will be wholly effected upon the broken or half kernels. In the last 85 case mentioned it is of course particularly desirable that the grain shall be well cleaned, either in its whole or broken condition, before decortication.

My invention is not restricted to any particular mode of operating upon the portion of the berry detached, either in breaking the kernels or in decorticating the half-kernels; but I suggest that, as a little valuable flour substance will be removed in these operations, it 95 will be better to perform any further reductions thereon, and also to perform the operation of reducing the fragments of bran for the separation of food substance therefrom, upon rolls.

In previous methods of grain-reduction it 100 has been impossible to produce a large percentage of coarse middlings or farina without bran adhering thereto. In the process described it is practicable to obtain a percentage

of such coarse middlings or farina hitherto entirely unknown in the history of the reduction of grain.

I claim as my invention—

5 The method hereinbefore described, which consists in splitting and dividing lobated grain through the crease and decorticating the half-kernels, then separating the impurities from the half-kernels, then reducing the half-kernels, and thereafter separating the inner bran-

film from the product of reduction, whereby a large percentage of pure food substance is produced, substantially as set forth.

In testimony that I claim the foregoing as my invention I affix my signature in presence 15 of two witnesses.

LOUIS GATHMANN.
